STEEL GIRDER FOR CONCRETE
STRUCTURES

Fritz Zollinger, Merseburg, Germany

Application September 17, 1932, Serial No. 633,642
In Germany September 17, 1931

3 Claims. (Cl. 72—109)

My invention relates to improvements in the erection of metal framed and reinforced concrete floors, walls, roofs and other supporting and enclosing parts of buildings, bridges, silos etc., and more particularly to improvements in special shaped steel girders or beams of the type which are made of relatively thin steel sheeting and which are in many cases preferred as framing—supporting—studding—and bracing elements in concrete structures where extreme lightness combined with strength and speedy erection are the chief considerations.

The principal object of the invention is to provide a girder of improved design made of steel sheeting for use in concrete structures of various kinds which can be more easily manufactured, and put onto the market at a considerably lower price than steel sheet girders of kindred types known heretofore.

Another object of the invention is to thus design the improved girder that it can be quickly cut into the proper lengths even by hand operated tools, viz. without the use of heavy machinery; and that it is an easy task even for not highly trained welders to join for re-use short remnant lengths, which otherwise would be useless, by autogenous welding or other welding or soldering processes, so that practically no waste occurs.

Another feature of importance of the steel sheet girders of improved design according to this invention is the fact that they can be closely piled up upon each other so that large numbers of girders can be packed into relatively small boxes, as far as their cross section is concerned, and that they can be easily shipped on account of their small total weight even into remote districts far from railroad traffic.

Still other objects aimed at by this invention and advantages obtained thereby will become apparent hereinafter to practitioners in the ferro-concrete building trade.

The nature and scope of the invention are briefly outlined in the appended claims and will be more fully understood from the following specification taken together with the accompanying drawings in which

Figs. 1 and 1a are cross sections, taken along lines I—I and II—II in Fig. 2, and showing by way of an example a concrete floor supported by girders according to this invention during and after erection.

Fig. 2 is a side elevation of a girder of improved design;

Fig. 3 is a perspective view of the girder, shown in Fig. 2;

Fig. 4 is a cross section through a shipping box showing a number of girders piled up therein;

Fig. 5 shows perspectively the lower tubular flange portion of the girder with a reinforcing rod 23 running therethrough and being embedded in a filling of concrete.

Fig. 6 shows a cross section, Fig. 7 a side view, and Fig. 8 a plan of another example of construction.

Fig. 9 shows a perspective view of another example of application of the invention.

Fig. 10 shows a perspective view of a further application of the invention.

Fig. 11 is a cross section of a detail of Fig. 9 to a larger scale.

Figs. 12—15 show concrete floors supported by girders, which are designed according to this invention, said floors serving to support a ceiling.

The girder or improved design consists of a web 10 of thin metal sheeting, preferably of mild steel; the lower edge of the web is formed with a tubular flange 20, while the upper edge is provided with tongues 30, 30' adapted to be bent away from the web preferably towards alternate sides, as best seen in Fig. 3, so as to act as bracing members when the upper section of the web is embedded into a layer of concrete 40.

The construction of a ferro-concrete floor in a building can be carried out with great speed and economy by means of the improved girders described above, in the following manner: The girders are placed upon the supporting walls in upright position by means of distance rods 50 and screw bolts 51 extending through holes 11 of which a number are provided in the girder in alignment to each other at a suitable distance from its tubular flange 20. In erecting the mold for the concrete floor brackets 60, 60' for supporting the sheeting boards 61, 61' are attached to the girders by means of clamping bolts 62 which extend through holes belonging to the set of holes 11 referred to above.

Whenever required according to static calculations viz. in consideration of the maximum load on the floor, reinforcing rods 80 are placed into position on the indented upper edge of the girders and other rods 82 may be passed through holes 12 provided for this purpose, whereupon the mold is ready for receiving the mixture of concrete.

After the concrete has become hardened and the sheeting has been removed, the lower section of the girders which is not embedded in the concrete may be suitably covered with fire resisting material, as diagrammatically indicated in dot and dash lines in Fig. 1a; or a ceiling—not

shown—may be attached viz. suspended by clamping elements from the system of girders carrying the concrete floor.

Various changes and modifications may be made in the structural details of girders of the improved design described above, without deviating from the spirit and the salient ideas of this invention.

For instance another set of holes 15 of preferably rectangular shape may be provided in the body of the web and supporting tongues 16, 16', laterally projecting from the web 10 at alternate sides of same as seen in Figs. 1-3.

Instead of forming the tubular flange 20 with a flattened edge portion 21 abutting against the web 10 as shown in Fig. 1a and being joined thereto by electric welding, a flange of modified design which is cheaper to make may be applied to advantage.

My experimental work has shown that a flange the extreme edge 22 of which extends into its tubular cavity, as shown in Figs. 1 and 5, possesses such stiffness that welding or otherwise joining the edges concerned can be dispensed with.

In Fig. 2 it is indicated by dotted lines how the bracing tongues 30, 30' may be temporarily bent upwardly so that sheets of expanded metal 90, wire netting or the like can be lowered onto the system of girders as reinforcing elements of particularly light weight, an important factor e.g. in case of solid roofs where a minimum of thickness and weight are desired.

Various other ways of using girders of the improved design as supporting, reinforcing, stiffening, bracing elements in floors, walls, roofs, columns, and like concrete structures will suggest themselves to practitioners and a few applications are shown by way of examples in Figs. 6-11.

In Figs. 6 to 8 the tongues 30, 30' are shown bent at different angles from those shown in the preceding figures, whilst the holes 15 and their corresponding tongues 16 are made longer, and tongues are also provided adjacent the holes 12 for the passage of the rods 80. A rod 82 is also shown as passing through one of the holes 15.

In Figs. 9 and 11 a T-iron 91, provided with spaced notches in its upper flange passes through the holes 11, in which it is secured by wedges 92, and serves to support the sheeting boards 61. Wires or rods may also be passed through the holes 11 to ensure a better hold of fire resisting material when this is applied.

Fig. 10 shows an arrangement wherein some of the tongues 30, 30' are bent vertically upwards, whilst others serve to hold sheets of expanded metal 90 in position. The reinforcing rod 23 is also curved upwardly at its free end so as to increase its engagement in the surrounding concrete.

Fig. 12 is a cross section of a floor in which the layer of concrete 40 of the girder supports a concrete floor 98. From this floor depend suspension rods 94, which together with the wires or rods 93, serve to support expanded metal 95 for a ceiling.

Fig. 12a shows in longitudinal section the use

of a girder according to the invention associated with a girder of I-section, this figure being at right angles to Fig. 12, but the wires and rods 93, 94 are omitted.

Figs. 13, 13a, 13b show in cross section, plan, and in section on the line I—I of the plan another application of the arrangement described in connection with Figs. 6 to 11. The spaces between the ribs of reinforced concrete may be left open or if desired filled in with bricks 98', preferably apertured bricks, known as "Hourdis".

In Fig. 14 the concrete 40' of the girder supports a reinforced plaster floor 99, whilst the rods 93 serve to support expanded metal sheets provided in a ceiling.

Fig. 15 shows a floor in which the girder is completely embedded in concrete.

What I claim is:

1. In a concrete structure a slab of concrete, which is reinforced by and structurally associated with a girder of special design, the latter comprising a sheet metal web, presenting a lower zone, adapted to take up tensile stresses, and an upper zone, the latter being embedded in the said slab of concrete and being provided along its top edge with bracing tongues, laterally extending therefrom, the tension zone of the girder which downwardly projects from underneath the slab of concrete, being provided along its lower edge with a tubular flange.

2. In a concrete structure a slab of concrete, which is reinforced by and structurally associated with a girder of special design, the latter comprising a sheet metal web, presenting a lower zone, adapted to take up tensile stresses and an upper zone, the latter being embedded in the said slab of concrete and being provided along its top edge with bracing tongues laterally extending therefrom, the tension zone of the girder, which downwardly projects from underneath the slab of concrete, being provided along its lower edge with a tubular flange,—spaced holes being provided in the upper section of the compression zone of the girder for the insertion of reinforcing rods, crosswisely extending therethrough.

3. In a concrete structure a slab of concrete, which is reinforced by and structurally associated with a girder of special design, the latter comprising a sheet metal web, presenting a lower zone, adapted to take up tensile stresses, and an upper zone, the latter being embedded in the said slab of concrete and being provided along its top edge with bracing tongues laterally extending therefrom, the tension zone of the girder, which downwardly projects from underneath the slab of concrete, being provided along its lower edge with a tubular flange,—spaced holes being provided in the upper section and in the lower section of the compression zone of the girder for the insertion of reinforcing rods, crosswisely extending therethrough,—the holes in the said lower section being of substantially rectangular shape and being formed with auxiliary tongues outwardly extending from the base of said holes.

FRITZ ZOLLINGER. 140
